[57] CLAIM

The ornamental design for a toilet seat, as shown and described.

DESCRIPTION

FIG. 1 is an top perspective view of a toilet seat showing my new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a right side elevational view thereof; and,

FIG. 7 is a left side elevational view thereof.

The broken line representation of a toilet in FIGS. 1 and 6 is for purposes of illustration only and forms no part of the claimed design.
